UNITED STATES PATENT OFFICE.

PETER McMULLEN, OF BUFFALO, NEW YORK.

CAR-BRAKE.

SPECIFICATION forming part of Letters Patent No. 487,681, dated December 6, 1892.

Application filed August 31, 1892. Serial No. 444,617. (No model.)

To all whom it may concern:

Be it known that I, PETER McMULLEN, a citizen of the United States, residing at Buffalo, in the county of Erie and State of New York, have invented certain new and useful Improvements in Car-Brakes; and I do hereby declare the following to be a full, clear, and exact description of the invention, such as will enable others skilled in the art to which it applies to make and use the same, reference being had to the accompanying drawings, and to figures of reference marked thereon, which form a part of this specification.

My invention relates to improvements in brakes employed specially upon railway passenger and freight cars, and has for its object an improved construction and arrangement of parts whereby the brake-shoe is applied to the upper part of the wheel and the employment of the cumbersome and dangerous brake-beam is avoided.

I will now proceed to minutely describe the manner in which I have carried out my invention and then claim what I believe to be novel.

In the drawings, Figure 1 is a side elevation of a car-truck with my improved brake attached. Fig. 2 is a top plan view of my improved car-brake. Fig. 3 is a detached detail view of the brake-shoe and its lever. Fig. 4 is an under side view of the car, showing the application of my improved brake to the air-cylinder; and Fig. 5 is a side view of the same.

Referring to the drawings, 11 are the wheels, 35 2 the upper cross-beam, 3 the lower cross-beam, and 4 the iron connecting-strips, of the car-truck to which my improved brake is applied. The framework to which the operative parts are secured consists of two similarly shaped side pieces 5 5, having arched ends extending over the wheels on each side of the truck. At the center of each side piece 5 is cut the rectangular recess 7, into which the upper cross-beam 2 of the truck is fitted, the 45 side pieces 8 8 extending down below the cross-beam 2 and rigidly secured thereto by the cross-strips 9, which are riveted to the side pieces 8 8, as shown, thereby firmly attaching the framework of the brake mechanism to the 50 car-truck over each set of wheels on either side. Between the pieces 5 5 are located the levers 10 10, which are pivoted at their lower

ends to the cross-bolts 11, which unite the pieces 5 5 at a point just above the horizontal center of the wheels. The upper ends of these 55 levers 10 10 are pivoted to the connecting-rod 12, having the turnbuckle 13, and the yoke 14 is in turn pivoted at its two ends to the two sets on either side of the truck at the points 15 15.

The lever 10 consists of a piece of metal 60 bent over upon itself, forming a recess 16, as shown in Fig. 3, in which at about the center is pivoted the brake-shoe 17, one for each wheel, as shown in Figs. 1 and 2. The point of friction of the brake-shoe is, as will be seen, 65 above the horizontal center of the wheel and extends to the upper point of the tread.

My improved brake mechanism just described is connected to the air-cylinder, as shown in Figs. 4 and 5, in which 18 is a shaft 70 journaled in the bearings 19. At or about its center are rigidly secured, upon opposite sides thereof, the crank-arms 20 20, at the outer ends of which are pivoted the connecting-rods 21 21, which have their other ends pivoted to the yokes 14 14, attached to the brake mechanisms at either end of the car. 22 is a supplemental crank-arm secured to the shaft 18, its outer end being pivoted to the piston-rod 23 of the air-cylinder 24, connected with 80 the force-pump of the engine. A coiled spring 25, one end of which is secured to the shaft 18 and the other end to the bearing 19, serves to assist in throwing the brake-shoes out of engagement with the wheels. 85

In case air is not used the brake mechanism described can be connected in any well-known way to the brake-wheels upon the platforms of the cars.

In operation the rod 12, being properly adjusted by the turnbuckle to give uniform contact of the brake-shoes, is forced by the power applied, so as to set the brake-shoes 17, pivoted to the levers 10, against the tread of the wheels entirely upon its upper portion, which 95 results in a bearing down upon the wheels, making the frictional contact correspondingly effective. It will be seen that my improved construction is all located above the truck, no brake-beam being employed, the presence 100 of which having always been a source of great danger, especially when the trucks leave the track in the derailment of a car, as in this event the brake-beam is invariably torn away

and dropped across the track, serving to throw the next car from the track and causing much greater damage than would occur with the use of my improved mechanism.

5 The sets 5 5 on each side of the truck could be additionally strengthened by rods extending across the truck from side to side and properly secured to the framework.

I claim—

- 10 1. A brake mechanism for railway-cars, consisting of a framework secured to the upper side of the truck and extending over the wheels, levers pivoted to the framework, and brake-shoes pivoted to the levers over the
- 15 wheels and located for bearing-down contact with the upper portion of the tread of the wheels, the upper ends of the levers being connected together and operated from the source of power, substantially as shown, and
- 20 for the purpose stated.

2. A brake mechanism for railway-cars, consisting of the two sets 5 5 and 5 5 of side pieces secured to the cross-beam on the upper side of the truck, the levers 10, pivoted to the securing-bolts 11, the brake-shoes 17, pivoted in a recess in the levers 10, so as to have frictional contact with the upper part of the wheel, the connecting-rod 12, with turnbuckle 13, and the yoke 14, pivoted to the brake mechanism and connected to the source of power, all combined and operating substantially as shown and described.

In testimony whereof I have signed my name to this specification in the presence of two subscribing witnesses.

PETER McMULLEN.
